UNITED STATES PATENT OFFICE

148,665

DESIGN FOR A ROBE OR SIMILAR ARTICLE

Samuel Valenstein, New York, N. Y.

Application July 16, 1947, Serial No. 140,314

Term of patent 3½ years

(Cl. D3—26)

To all whom it may concern:

Be it known that I, Samuel Valenstein, a citizen of the United States of America, residing in New York, county of New York, and State of New York, have invented a new, original, and ornamental Design for a Robe or Similar Article, of which the following is a specification, reference being had to the accompanying drawing, forming part thereof.

Fig. 1 is a front view of a robe or similar article, showing my new design.

Fig. 2 is a rear view thereof.

Fig. 3 is an enlarged view of the pocket portion illustrating the design in detail.

I claim:

The ornamental design for a robe or similar article, substantially as shown and described.

SAMUEL VALENSTEIN.
